Edward A. Pawson and George J. Custer,
Long Beach, Calif.

Application January 14, 1957, Serial No. 44,492

Term of patent 3½ years

(Cl. D74—10)

FIG. 1.

FIG. 2.

FIG. 3.

The paste dispenser is formed of a plastic material and the tip thereof is serrated or grooved as shown in Figs. 1 and 3.

We claim:

The ornamental design for a paste dispenser or the like, substantially as shown and described.
